DEPARTMENT STORE MACHINE

Frederick L. Fuller and George F. Daly, West Orange, N. J., assignors to International Business Machines Corp., New York, N. Y., a corporation of New York

Application December 4, 1935, Serial No. 52,766

17 Claims. (Cl. 164—112)

This case relates to recording machines.

In particular, the invention deals with a machine for recording sales transactions in large stores such as department stores. The sales transaction is recorded by the machine on a sales slip or the like in the form of a printed record, and is also recorded on a tabulating card in the form of a punched coded record. The printed sales slip is usually given to the customer, while the punched card is retained in the store and subsequently used to control tabulating machines for tabulating the information on the card.

Broadly, the invention has for its object to provide a novel, improved, machine for recording data pertaining to the article sold, to the clerk making the sale, and to the customer.

More specifically, an object of the invention is to provide novel card perforating means, and in such means to provide a novel punch pin guide and holder.

Another object is to provide a new key-controlled mechanism to enter an item in differentially operable means, such as item indicating elements, type members, or punching members.

Still another object is to provide a novel form of item designation on a record medium, such as a slug, token, or check, and further to provide novel sensing means for reading the item designation and transferring the value denoted by the designation to printing and punching means.

It is also an object to provide novel means for transferring the setting of punching means to other recording means, such as type wheels.

Other objects are to provide novel card ejecting means and novel positioning means for the sales slip.

Still other objects will appear in the following parts of the specification and from the drawings, in which:

Fig. 1 is a plan section through the machine; Figs. 2 to 6 are respectively sections along lines 2 to 6 of Fig. 1;

Fig. 6a is a detail of an item wheel on a punch slide with the item wheel in section;

Figs. 7 and 8 are sections along lines 7—7 and 8—8 of Fig. 1, respectively;

Fig. 9 is a section along lines 9—9 of Fig. 3;

Fig. 10 is a section along lines 10—10 of Fig. 1;

Fig. 11 is a section along lines 11—11 of Fig. 1;

Fig. 12 shows the tabulating cards punched in the machine;

Fig. 13 shows a sales slip on which a record is printed on the machine;

Fig. 14 shows the customer's account number token;

Fig. 15 shows the token representing the kind of article sold;

Fig. 16 is a section along lines 16—16 of Fig. 2;

Fig. 17 is a section along lines 17—17 of Fig. 2;

Fig. 18 is a detail section taken along lines 18—18 of Fig. 1;

Fig. 19 is a plan view of the punching mechanism of the machine with covering parts removed to expose interior mechanism;

Fig. 20 is a detail, end, view of a punch slide, the punch carried thereby, a stripper bar, and part of the punch operating or pressure plate;

Fig. 21 is a section on lines 21—21 of Fig. 20;

Fig. 22 is the timing diagram, and

Fig. 23 is a perspective view of the machine.

Following is the list of items which may be recorded for each article sold and the number of denominational orders assigned to each item. To each denominational order of an item, one card column is assigned.

	Columns
Price of one article—maximum \$9999.99	6
Transaction (cash take, cash carry, charge take, charge carry)	1 20
Sales clerk	2
Customer's account number	6
Department to which the machine is assigned	2
Kind of article	3
Date (day—2 cols., month—2 cols.)	4 25
Total	24

For illustration, the Hollerith code of punching a card is used. This code employs a single perforation in one of the index point positions of a card column to designate a number. Thus numbers 9, 8, 7—0 are designated by a single perforation in one of positions 9 to 0 of a card column (Fig. 12).

Briefly, the manner in which a sale is recorded is as follows: The clerk writes on sales slip S (Fig. 13) the name and address and other supplementary information relating to the sale. For convenience, when the clerk writes on the slip the supplementary information referred to above, he may through a carbon sheet simultaneously inscribe this information on the blank portion of the first card to be punched. Each slip has space at the bottom to receive three lines of printed data, each line relating to the sale of a separate one of several articles sold to one customer. Three is considered the usual maximum number of articles sold to one customer in one store department. If it is desired to record more than three sales on one slip, a longer sales slip may be provided.

For each printed line of data on the slip S, one card T (Fig. 12) is punched. For three articles and three lines of printed data on one sales slip, three cards are punched.

The date and department items are pre-set in the machine. The kind of article and the customer's account number are represented respectively by tokens G and P (Figs. 14 and 15) bear-

ing identifying configurations. These tokens are inserted in the machine to control the setting of the punching and printing means for recording the kind of article and the customer's charge account number. A ten key board is operated to set up the amount or price, the kind of sale, and clerk's number. A sales slip S is placed in printing position. These three steps, namely: token insertion, key operation, and sales slip positioning, may be carried out in any order. After these three steps have been taken, the operator inserts a card T in the punch section. This insertion unlocks a manual actuator for a cycle of operation.

15 During this cycle, the card is punched and ejected and the first line s of data is printed on the sales slip. Should it be required to record more than one sale on the same slip, the slip is re-positioned, and the clerk sets up on the keys 20 a new amount and repeats the setting up of the keys for the kind of sale and clerk's number. A second card is inserted and a second cycle of the actuator effected, resulting in punching the second card with the data of the second sale and in 25 printing the second line s on the sales slip.

A detail description of the machine follows:

There are twenty-four punch slides or carriers 10 (Figs. 1, 2, 3, and 19) one for each card column to be perforated. Each slide 10 is a narrow 30 elongated bar slotted longitudinally to provide a card receiving slot 11 (Figs. 6, 8, and 20). Each slide holds one punch pin 12. These punch pins 35 are narrow, rectangular, in cross-section and perforate elongated rectangular holes in the card. The punch pins must be smoothly and accurately mounted in their guiding holes and must be capable of moving accurately into their die holes. It is difficult to bore and accurately machine and 40 finish an internal, rectangular-shaped, elongated, punch guiding and receiving hole. The following means and method have been devised to overcome the above difficulty and to provide a smooth, accurate, guiding aperture and die hole for the punch.

45 Referring to Figs. 20 and 21, one side of the slide 10 is milled above and below slot 11 with an open, angular, channel for accommodating half the cross-section of a punch pin 12. This open channel is accurately finished. A pair of plates 50 13 and 14 are also milled with open, angular, channels which are finished accurately and of dimensions to accommodate half the cross-section of the punch pin. Plate 13 is then welded to the slide above slot 11 and plate 14 welded to the 55 slide below slot 11 with the channels in the plates and slide facing each other to form rectangular apertures above and below slot 11 for mounting and guiding a punch pin 12. The slide and plate 13 thus provide an upper punch holder and guide 60 and the slide and plate 14 provide a lower punch die.

65 The twenty-four slides or punch pin carriers 10 are arranged in parallel vertical planes and are slidably guided for horizontal movement within their own planes by the slots of upper and lower comb bars 15 and by the surfaces of cross bars 16 to which the comb bars are secured. These cross bars are suitably held in rigid relation to the vertical frame plates 17 and 18 carried by base plate 19. The portions of the slides adjoining card-receiving slots 11 ride along comb bars 20 and 21 (see Fig. 6), which thereby assist combs 15 and bars 16 in restricting the carriers to 70 slideable movement in their own planes. At the same time, the confronting vertical sides of comb bars

20 and 21 serve as side guides for the card T to assist in locating the card properly when the card is inserted through slots 11 into punching position. The card is inserted lengthwise so that when in punching position, each of its columns is 5 in the plane of one punch slide in position to be perforated by the punch mounted by the slide.

Each of the punch slides is separately adjustable lengthwise to one of ten positions to bring the punch 12 above one of the index point positions 10 9 to 0 of the card column in line with the slide. The punch pin 12 is provided, near its upper end, with a transversely extending button 22 resting on a rail 23 and by this engagement, the rail normally holds the punch pin above card slot 11 and 15 clear of the card in punching position. There is one rail 23 for each punch and the rails are arranged similarly to the punch slides so that during movement of a slide to a differential position, the punch moves between a pair of rails with its 20 button 22 riding on top of one of the rails.

Rails 23 are secured at opposite ends between the locating teeth of a pair of transversely extending comb bars 24 and 25. To the upper surfaces of the latter bars is secured a horizontal plate 26 which covers all the possible differential positions to which the twenty-four punches may be adjusted. Rails 23, bars 24 and 25, and plate 26 form a rigid punch operating assembly of which rails 23 constitute punch pin guiding and restoring or stripping means and plate 26, the punch pin depressing means.

30 Bars 24 and 25 of the punch operating assembly are formed at each end with reduced circular portions seated in slots 27 (Fig. 5) of pairs of 35 levers 28 and 29, one pair at each side of the punch operating assembly. Levers 28 and 29 are pivotally connected to each other at their adjacent ends and pivoted intermediately on studs 30 extending from the vertical side frames 17 and 18. 40

Levers 28 are connected to depending links 31 (Figs. 5, 8, 19), formed at their lower ends with vertically elongated slots 31' (see particularly Figs 5 and 8). A lever 32 is secured to the right hand end of a shaft 33 (as viewed in Fig. 1). 45 Shaft 33 is journaled by frame plates 17 and 18, and at its left end, the shaft rigidly carries an arm 32' parallel to arm 32a of lever 32. Arms 32a and 32' are provided with pins 320 which extend into slots 31' of links 31. At their outer ends, arms 32 and 32' have pins 321 extending into slots 322 formed in the sides of a bail 34 freely pivoted on a rod 35 carried by frames 17 and 18. The 50 sides of bail 34 are connected by cross bar 36 extending above all the slides 10 and adapted to engage in any of ten spaced notches 37 formed along the upper edge of each slide.

When the slides have been variously set in one of their ten differential positions, a cam 38 on cam shaft 39 (see Figs. 1, 3, and 5) acts on 55 arm 32b of lever 32, to rock the lever and its shaft 33 clockwise (Fig. 5). The first portion of the movement of shaft 33 causes arms 32a and 32' to rock bail 34 downwardly by camming coaction of pins 321 with the upper, inclined, portions of slots 322. The bail 34 is moved down to dotted line position, Fig. 5, and bar 36 is thereby moved into roughly aligned notches 37 of the twenty-four slides 10. When bar 36 is fully seated in these notches 37, it 60 aligns the notches perfectly, and thereby locks all slides 10 accurately, with each slide occupying the exact differential position for which it had been adjusted. Subsequent to this action of bar 36, as shaft 33 continues its clockwise move- 65

ment, pins 320 of arms 32a and 32' reach the lower ends of slots 31' and start to depress links 31, thereby rocking levers 28 clockwise and levers 28 anticlockwise (Fig. 5) about pivots 30. 5 As a result, levers 28 and 28 depress the punch operating assembly. Plate 26 of the assembly thereupon engages the heads of all twenty-four punches 12, and presses them through the selected index point positions of the card T in 10 punching position.

While arms 32a and 32' are depressing the punch assembly, pins 321 which have cleared the inclined, upper portions of slots 322, travel along edges 323 of slots 322. These edges are 15 concentric about shaft 38 when bail 34 is in dotted line position, Fig. 5, so that movement of pins 321 along these edges does not tend to move the bail, but serves to hold the ball in contact with limit stop pins 324.

20 When depression of the punch assembly, and, consequently, the punching of the card, is completed, a cam 38' on shaft 38, complementary to cam 38, acts on arm 32c of lever 32 to rock the latter counterclockwise (Fig. 5). During the 25 first part of this movement, pins 320 rise idly along slots 31' of links 31, and pins 321 move idly along edges 323 of bail 34. Before the pins 321 leave edges 323, pins 320 engage the upper ends of slots 31' and start elevating links 31. 30 This action of the links raises the punch operating assembly, and during the rise of the assembly, its restoring or stripping bars 23 engage buttons 22 of the punches to lift the latter, thus stripping the punches from the card and 35 storing them to initial, raised, positions.

When the punch pins have been lifted clear of the card, pins 321 move into the inclined portions of slots 322 of bail 34 and start rocking the bail clockwise (Fig. 5). Thus, during the latter 40 portion of the punch restoring action, bail 34 is rocked in a direction to release locking bar 36 from notches 37 of the slides, which are thus left free to be restored.

The timing of the above punching and locking 45 actions will be more specifically given in the summary.

The manner in which slides 10 are moved lengthwise to be set differentially will now be explained. Each slide 10 is individually adjustable to set its punch 12 in one of ten differential 50 positions 0 to 9. In the initial position of a slide, at the right end of its travel, as viewed in Figs. 6 and 8, the slide is in "0" position. From this latter position, it may move one to nine 55 steps to the left to set its punch 12 at successive positions "1" to "9" for perforating the corresponding 1 to 9 index point positions of a card column.

For convenience, in the following parts of the 60 description and in the drawings, the common reference character for similar elements may be suffixed by a distinguishing character to indicate the item to which the element relates. Distinguishing characters p, g, b, d, a, t, and c will 65 be used to denote respectively elements related to purchaser's account number, kind of goods, store department, date, amount or price of an article, kind of transaction, and clerk's number. The arrangement of the several groups of slides is indicated in Fig. 1. Reading left to right in 70 Fig. 1, there are six account number slides 10p, two department slides 10b, three kind of goods slides 10g, four date slides 10d, six amount slides 10a, one transaction slide 10t, and two clerk number slides 10c.

The setting of the date and department slides and the corresponding printing elements will be explained first.

Date and department setting

Referring to Figs. 2 and 23, housing 40 of the machine has an opening at the top which is closed by a hinged door 41 located above cog-toothed wheels 42 (Figs. 1, 5, and 17). The four wheels 42 at the left correspond to the tens and units of days and tens and units of months; the next three wheels 42 correspond to the kind of goods; the two following wheels correspond to the tens and units of the department number; and the last six correspond to the account 15 number. The door 41 is opened to provide access to the wheels 42 and at the beginning of each day, the operator manually sets day wheels 42. At the beginning of each month, the month wheels 42 are set. The department wheels 42 20 are set when the machine is assigned to record sales in a certain store department. Each of these wheels 42 has its teeth meshed with the teeth of type wheels 43 rotatably carried on a shaft 44 (see also Figs. 1, 5, and 17).

There are ten teeth on each type wheel 43, each tooth faced with a type legend 0 to 9 for printing these characters. When a wheel 42 is rotated, it rotates the meshed type wheel 43 to present the selected type at the printing line.

As shown in Fig. 17, each cog-toothed wheel 42 is carried by the left end of a nested shaft 45, which at the opposite end carries a wheel 46 (see also Figs. 1, 2, and 8) which is in mesh with rack teeth 47 formed along the upper edge 35 of a punch slide 10. The four date wheels 42 are thus geared to the four date slides 10d, the three kind of goods wheels 42 are geared to slides 10g, the department wheels 42 are geared to slides 10b, and the account wheels 42 are geared to 40 the six slides 10p.

When the date and department wheels 42 are adjusted, through connected gear wheels 46 meshed with teeth 47 of the corresponding punch slides, they advance the latter slides to position their punches for perforating the date and department columns of a card with the coded designations of the date and department items. At the same time adjustment of the date and department wheels 42 sets the meshed type 50 wheels 43d and 43b (see Fig. 17) to print the date and department data.

The control of the account number and kind of goods slides 10p and g and the corresponding type wheels 43 by tokens P and G will now be 55 explained.

Token setting

Token P and G shown in Figs. 14 and 15 are preferably made of metal, though they may also 60 be made of any other suitable material such as stiff paper, hard rubber, or composition material. The token may also be referred to as a check, slug, or record member of which it is the equivalent. To represent a digit on the token, the latter is 65 formed with a vertical slot 48 proportional in length to the value of the digit. Thus "0" is represented by a slot of zero length or a solid portion of the token, "1" is represented by a short slot, "2" by a slot twice the length of the 70 "1" slot, and so on, the slot representing "9" being the longest. Each denominational order of the number designated by the token is represented in a different vertical portion of the token, 75 as indicated in Figs. 14 and 15. Each token also

has a horizontal slot 49 near the bottom which is located eccentrically to the vertical center line of the token. Rigidly secured to frame plate 17 is a frame 60 (see Figs. 1, 8, and 18) constructed to provide a pair of separated pockets or receptacles 51 and 52 to respectively receive tokens P and G. The lengths of the pockets are the same but their widths differ to correspond to the different widths of the two tokens. The top of housing 60 is cut out to permit insertion through the housing of the tokens into their respective pockets 51 and 52. When a token is fully inserted in its pocket, its lower edge engages the top of a vertically slideable member 53 and depresses the latter against resistance of a spring 54. The spring connects member 53 to a pivoted latch lever 55 which has a lug 56 engaged with the advanced portion 57 of the front edge of member 53 when the latter is in upper position. There are two such members 53 and companion latches 55, one member and latch for each of pockets 51 and 52.

When a member is depressed by insertion of a token, its front edge portion 57 rides off lug 56 of the companion latch 55 permitting spring 54 to rock the latch anticlockwise (Fig. 8) to move the tooth 58 at its upper end into slot 49 of the token. This locks the token in correct position in its pocket.

30 A token must be inserted with the front face, seen in Figs. 14 and 15 towards the operator, positioned at the front of the machine (see Fig. 23) in order to bring the several columns or orders of designation slots into proper correlation with the denominational order mechanism for reading these slots. By locating the locking slot 49 of a token off center, the operator is compelled to insert the token correctly otherwise the locking slot will be out of line with the tooth 58 of latch 55 and not in position to receive the locking tooth, in which case, as soon as the clerk relieved the pressure of his fingers on the token, member 53 would be raised by spring 54 to eject the token to inactive position.

45 The reading means for the token designations comprises the six account number punch slides 10p and the three kind of goods punch slides 10g. These slides are formed at their forward, left hand ends (Fig. 8) with steps 59 arranged in echelon, one behind another, and at different distances from the longitudinal center line of the slide. The values corresponding to the different steps 59 are indicated alongside the steps. The extreme forward edge of the slide represents 55 value 0.

50 Each of slides 10p and g, as well as the price, transaction, and clerk number slides 10c, t, and c has a pin and slot connection at its rear end with the upper end of an arm 60. The several arms 60 are freely pivoted on a rod 61 carried between frame plates 17 and 18. Each arm 60 is separately connected to a spring 62. The springs urge the arms 60 and connected slides towards the left (Figs. 6 and 8). Initially, the arms cannot move to the left because they are held back by engagement with a common bar 63 secured to the upper ends of arms 64 and 64', rotatably mounted on rod 61 (see also Fig. 3). The department and date slides are not connected to arms 60, leaving room below the latter slides for locating arms 64 and 64'. The arm 64' is pinned to a link 65 (Figs. 3 and 6) which is forked at the rear to slidably receive cam shaft 39. Link 65 has a follower roller 65' riding on cam 66 of cam shaft 70 75 39. In home positions of shaft 39 and cam 66, the

roller 65' is on a high dwell portion of the cam so that link 65, cross bar 63, and arms 60 are held at their right hand limits (Figs. 6 and 8). Slides 10p, g, a, t, and c connected to arms 60 are therefore initially maintained in "0" positions.

When cam shaft 39 is rotated, counterclockwise, (Fig. 6) by means to be described further on, roller 65' rides on the dwell portion of cam 66 and along a drop of the cam. Under the influence of springs 62, arms 60 move counter-clockwise (Fig. 6) and through engagement with bar 63 rock the latter in the same direction, causing link 65 to move to the left and its roller 65' to follow the contour of cam 66. Arms 60 move under the influence of their individual springs 62 and correspondingly move their connected slides until the latter are arrested differentially.

When the sale is for cash, a charge account token P is not inserted in the pocket 51 and similarly when it is not necessary to record the kind 20 of merchandise, token G is not inserted in its pocket 52. When a token is not inserted, it is required to maintain its reading, punch, slides in their 0 positions. This is done as follows: In the absence of a token from its pocket, the associated member 53 is in upper position and its high or advanced portion 57 is engaging lug 56 of associated latch 55 to maintain the latter at its clockwise limit (Fig. 8). Latch 55 has a pin and slot connection with one of two bell crank levers 67, there being one such lever for each latch. The upper end of each lever 67 is formed with a transversely bent lug 67' extending across the group of token reading and punch slides 10g or p. When a latch 55 is in clockwise, non-locking position, through its connection with a lever 67 it holds the latter at its counterclockwise limit in which the stop lug 67' of the lever is in front of steps 59-8 of the group of associated punch slides 10p or g. When so positioned, the stop lug 67' will arrest advance of the slides before they have moved more than a slight amount from their "0" positions. When the slides are later aligned by bar 38, in the manner previously explained, they are set accurately in "0" positions.

55 In above manner, the absence of a token G from pocket 52 results in slides 10g being held in their "0" positions, while the absence of a token P from pocket 51 causes slides 10p to remain in "0" positions.

When a token is inserted, the associated latch 55 rocks anticlockwise (Fig. 8) to move its tooth 58 into notch 49 of the token, locking the latter in its pocket. As a latch rocks anticlockwise, it moves connected lever 67 clockwise to lower stop lug 67' out of the path of advance of the associated slides 10. The latter may now move to read tokens P and G.

Under the influence of the springs 62, arms 60 connected to slides 10p and g move towards tokens P and G in pockets 51 and 52. If a token has a solid "0" designating portion in front of a punch slide, the slide will be arrested when its front edge engages the token and will be set in "0" position. If the token has a vertical, item 63 designating slot 48 equivalent to value 1, 2, 3-8, or 9 in front of the slide, the latter will move into the slot until the step 59 corresponding to the length of the slot engages the solid portion of the token above or below the slot. Thus, slots 48 of lengths 1, 2, 3, or 4 permit the slide to move 1, 2, 3, or 4 differential distances and arrest the slide when its step 59-1, 2, 3, or 4 engages the part of the token above the slot. Slots 48 of lengths equivalent to 5, 6, 7, 8, or 9 arrest the 70 75 80 85 90 95 100 105 110 115 120 125 130 135 140 145 150 155 160 165 170 175 180 185 190 195 200 205 210 215 220 225 230 235 240 245 slide after the latter has moved 5 to 9 differential distances by engagement of steps 58—5 to 9 with the part of the token below the slot.

As the slides 18p and g advance 1 to 9 differential distances, their punches 12 move to corresponding positions for punching the 1 to 9 index point positions of the account number and kind of goods columns of a tabulating card.

Further, as slides 18p and g move forward to 10 their differential positions under control of tokens P and G, their rack teeth 41 coact with the meshed toothed wheels 42 of nested shafts 45 to turn these shafts correspondingly to the movement of the slides (see Figs. 1, 8, and 17). Cog- 15 toothed wheels 42 of these shafts 45 meshed with toothed type wheels 43p and g and set the latter for printing the account number and the kind of goods data corresponding to the setting of the slides 18p and g.

20 During the final portion of the cycle of shaft 38, cam 66 acts on roller 68' to move link 65 to the right which causes ball bar 63 to rock clockwise and pick up the variously positioned arms 66 and return them and their connected slides to 25 their "0" positions. Slides 18p and g thereby withdraw from tokens P and G.

After slides 18p and g are restored, a cam 68 (see Figs. 2, 3, 6, and 8) on shaft 38 rides past the lower, nose end of a lever 69 and rocks the 30 latter clockwise. Lever 69 is connected to a link 70 which has a transversely extending pin 71 passing through aligned slots 72 of the two latches 58. When lever 69 is rocked clockwise, through link 70 and pin 71 it moves latches 58 in the same 35 direction, releasing teeth 58 from slots 49 of the tokens. The retraction of the latches again places stop lugs 67' of levers 67 in front of the "9" stops 59 of slides 18p and g. At the same time, springs 54 raise members 63 to partially eject the tokens, 40 which then protrude above the top of housing 60 to be conveniently removed by the operator.

The setting of the nine remaining punch slides; 1. e., the amount, transaction, and clerk number punch slides 18a, t, and c and the corresponding 45 type wheels 43 is effected under control of a ten key keyboard, as will now be explained.

Ten key control

There are ten keys 75, one for each of digits 0 50 to 9, as shown in Figs. 1 and 23. These keys are mounted for vertical movement in the frame (see Fig. 4) and their stems are bent transversely, as shown in Fig. 2 to place their lower portions in parallel planes, side by side.

55 The disposition of the various key stems is indicated at the bottom of Fig. 2 by the digital values to which the stems and keys correspond. The lower ends of the key stems are located side by side, in horizontal, transverse alignment, and 60 pivotally connected to the horizontal arms of bell crank levers 76 freely pivoted on a shaft 77. The vertical arms of levers 76 terminate in horizontally aligned nose portions 76', each in front of one of ten stop fingers 78. These stop fingers are 65 rigidly mounted on a shaft 79 and arranged with in the same parallel, spaced, planes as levers 76, as indicated in Fig. 2. The fingers 78 are also 70 rotatively displaced about their shaft 79 in the order indicated in Fig. 4. Accordingly, each finger 78 must move a different distance counter-clockwise to reach the nose portion 76' within its plane.

The left end of shaft 79 (as viewed in Fig. 2) 75 rigidly carries a pinion 80 meshed with a wide gear drum 81 freely, rotatably carried by a shaft

82. Meshed with the top of drum 81 are nine toothed item indicating wheels 83. Each wheel 83 has ten teeth marked on their faces with indicating numerals 0 to 9 to be viewed through a sight opening 84 in the top of casing 40 (see Fig. 23).

Indicating wheels 83 are freely rotatably mounted on a shaft 85 journaled between frame plates 47, 86, and 87 (see Fig. 2). The wheels 83 lie between the spaced sides of an H-shaped carriage 88 (see also Fig. 1). The sides of the carriage, at their front ends, are forked to slidably receive shaft 85. At their rear, the carriage sides are formed with threaded holes for coaction with the threaded portion of a shaft 89.

Carriage 88 is thus mounted on shafts 85 and 10 89 for slidable movement along the shafts to be advanced by rotation of shaft 89.

Shaft 89 is rotatably journaled between frame plates 47, 86, and 87. Rotation of shaft 89 20 through coaction of its threaded portion with the threaded apertures of the carriage effects movement of the carriage along shafts 85 and 89. As the carriage moves along these shafts, it slides 25 wheels 83 along shaft 85.

In the initial, home, positions of the parts, the carriage is at the extreme right of its travel (as viewed in Figs. 1 and 2) and the item wheels 83 are entirely clear of all nine right hand punch slides 18a, t, and c. Each step of movement of 30 the carriage to the left (Fig. 1) will move one of wheels 83 out of mesh with drum 81 and into mesh with rack teeth 41 of the unit order slide 18c. Thus, the first step of movement of the carriage brings the first wheel 83 from the left 35 (Figs. 1 and 2) clear of drum 81 and into mesh with teeth 41 of the right hand or unit order slide 18c. The next step brings this first wheel 83 into mesh with the second or tens order slide 18c, and, at the same time, moves the second 40 wheel 83 into mesh with the units order slide 18c. In this manner, successive steps of travel 45 of the carriage mesh the wheels 83 successively with the slides 18a, t, and c. At the end of nine steps of transverse movement of carriage 88, all nine wheels 83 will have moved off drum 81 and into mesh with the nine slides 18a, t, and c.

The transverse movement of carriage 88 is 50 effected under control of keys 75. Each time a key 75 is depressed to enter a value in a wheel 83, it causes a step of movement of carriage 88. Should the keys be depressed nine times to set up the nine wheels, then all nine wheels will be meshed with all nine slides 18a, t, and c. There is one key operation required for the kind of 55 sale and two key settings for the clerk's number. When the price of the article is the maximum six denominational order figure, six key operations are required to set the price. Thus, the maximum possible settings are nine. However, the price may be less than a six order figure, for example, 8.50 in which case only three wheels 83a will be set in addition to the setting of the one wheel 83t and the two wheels 83c, making a total of six settings, so that the last three 60 wheels will remain on drum 81 and will not be meshed with the slides. The other six, key-set, wheels 83 will be in mesh with the first six slides 18 from the right (Fig. 1). The three left hand slides 18 will not be in mesh with any of wheels 70 65 83.

The setting of the slides 18a, t, and c is effected by their advance under control of wheels 83 75 meshed therewith, in a manner which will be brought out later. Unless provision were made 75

to the contrary, the slides 10a not meshed with wheels 83 would move unimpeded to their "9" positions, resulting in a wrong record of the price being punched and printed. To avoid this error, the slides 10a not in mesh with wheels 83 must be restrained from advancing beyond their "0" positions. For this purpose, the left leg of carriage 88 (as viewed in Figs. 1 and 2) is formed at its front end with a depending laterally extending finger 90 (see also Fig. 18) which lies in front of all nine slides 10a, t, and c when the carriage is in the initial, right hand position.

Finger 90 when in front of a slide blocks advance of the slide beyond its "0" position. When the carriage moves one step to the left to mesh the first wheel 83 with the first slide, then finger 90 moves away from the front of the first slide. As successive steps of travel of the carriage are effected to successively mesh the wheels 83 with the slides, the blocking finger is displaced from in front of the successively meshed slides. At the end of nine steps of travel, all nine wheels 83 are meshed with slides 10, and finger 90 is completely displaced to one side of the slides.

Pinion 80 of shaft 78 and item indicating wheels 83 are both in mesh with gear drum 81, and are of equal diameters so that the pinion and wheels move through equal arcs upon rotation of the drum. Indicating wheels 83 and shaft 78 thus have ten corresponding differential positions. These ten positions of a wheel 83 are defined by its indicating teeth 0, 1, 2-9 while the corresponding positions of shaft 78 are defined in the same order by stop fingers 78-0, 1, 2-9.

Referring to Fig. 7, shaft 82, on which drum 81 is rotatably mounted, rigidly carries a pinion 82 (see also Figs. 1 and 2) meshed with a gear 83 rotatably mounted on a shaft 84 carried by the frame plates 86 and 87. Rigid with the side of gear 83 is a pinion 85 meshed with a gear sector 86 which is freely pivoted on a stud 87 carried by frame plate 86. A spring 88 connected to gear sector 82 urges the gear sector clockwise (Fig. 7). Sector 86 has a travel of about 40° and the ratio of gearing 86, 85, 83, 82, 81, and 83 is such that the full stroke movement of sector 86 is capable of producing eleven revolutions of wheels 83, more than sufficient to move each of the nine indicating wheels 83 through an entire revolution.

Shaft 82 has fixed to it an arm 89 adjacent the side of drum 81. In the initial position of the parts, arm 89 is engaging the free end of a pawl 100 pivoted to the side of drum 81 and urged by a spring 100' towards arm 89 and into limiting engagement with a pin 101 extending from the side of the drum. When shaft 82 is rotated clockwise, its arm 89 coacts with pawl 100 to rotate drum 81 in the same direction. During the counterclockwise, restoring, revolutions of shaft 82, its arm 89 will withdraw from pawl 100 and at each revolution, the arm will ride past the pawl, spring 100' yielding to permit the pawl to be cammed aside. Thus, arm 89 and pawl 100 provide a one-way, clockwise, driving connection between shaft 82 and drum 81. Drum 81 is never moved counterclockwise, as will later be brought out, but is moved only clockwise by the aforesaid one-way driving connection, and under control of pinion 80 with which it is meshed.

Drum 81 cannot move clockwise unless pinion 80 and its shaft 78 are free to rotate counterclockwise (Figs. 4 and 16). Shaft 78 fixedly carries a disk 102 (see Figs. 1, 2, and 16) which has 75 ten teeth 103, one of which is normally in en-

gagement with the nose end 104' of a bell crank lever 104. Teeth 103 are spaced correspondingly to the spacing of stop fingers 78 about shaft 78. When nose end 104' is engaged with a tooth 103, shaft 78 cannot rotate counterclockwise and drum 81 is not free to be rotated clockwise.

Lever 104 is rotatably carried by shaft 77 and is urged counterclockwise (Figs. 4 and 16) to engage its nose end 104' with a tooth of disk 102. The horizontal arm of lever 104 is bent angularly to provide a transverse lug 106 extending under the left hand arm of a bail 107 freely pivoted on shaft 77.

The cross bar 107' of the bail underlies the lower edges of the horizontal arms of all ten bell crank levers 104 which are pinned to the ten keys 78 (see Fig. 4). Spring 105 acting through lever 104 and its lug 106 urges bail bar 107' upwardly to maintain contact with the lower edges of the horizontal arms of levers 104 and in so doing, the spring helps to force keys 78 to their upper positions. The keys are additionally urged to upper positions by springs 108 acting on levers 104.

Riveted to the left side of bail 107 is a plate 109 having two sets of reversely inclined ratchet teeth 110. Each set of teeth 110 coacts with one of the end teeth 111 of the full stroke toggle pawl 112. A spring 113 acting on the pawl holds it set in either clockwise or counterclockwise position.

When any of the ten keys 78 is depressed, it rocks the connected lever 104 clockwise (Fig. 4) which depresses common bail 107 and the toothed member 109 carried by the bail. Once depression of a key is begun, the key cannot rise again until the full down stroke has been completed due to restraining coaction between the lower tooth 111 of pawl 112 with the lower set of teeth 110 of member 109. When a full down stroke of the key is made, then upper shoulder 114 of member 109 strikes projection 115 of pawl 112 and rocks the pawl counterclockwise. When the operator releases pressure on the depressed key, springs 105 and 108 combine to force the key to its upper position and during restoration of the key, upper tooth 111 of pawl 112 engages with the upper set of ratchet teeth 110 of member 109 to prevent depression of the key before it has finished its up stroke. Just before the end of the up stroke of the key and of bail 107, the lower shoulder 114 of member 109 strikes lug 106 of the pawl and causes return of the pawl to initial clockwise position.

At the beginning, all nine item indicating wheels 83 are sitting on top of drum 81, each wheel at zero position, and correspondingly shaft 78 is at zero position with detent 104' engaging a tooth 103 of disk 102 to prevent rotation of the shaft 78, drum 81, and wheels 83 under the influence of spring 88.

When any of the keys is depressed, it actuates the connected lever 104 to place the nose end 104' of the lever in the path of rotation of the stop finger 78 which is in the same plane. Further, when the lever 104 is actuated, it acts on bar 107' to rock bail 107 clockwise (Fig. 4). The bail in turn acts on lug 106 of bell crank lever 104 to rock the lever clockwise, opposed by the pull of spring 105. As a result, detent end 104' of lever 104 is released from the teeth of disk 102. There is nothing now to restrain rotation by spring actuator 88 of shaft 78, its pinion 80, drum 81, wheels 83, gears 82, 83, 85, and 86. Shaft 78 and the other elements of the above gear train, when released by detent 104', rotate under the influence 78

of spring 88 until the nose end 76' of the lever 76 connected to the depressed key is engaged by the associated stop finger 78. On the up stroke of the key, connected lever 76 returns in a counterclockwise direction (Fig. 4), withdrawing its nose end 76' from the stop finger 78 engaged with the nose end and releasing shaft 79 for a supplementary rotation counterclockwise. During the upstroke of the key, spring 105 also restores lever 104 to replace its detent end in the path of rotation of a tooth 103 of disk 102, thus arresting the supplementary movement of shaft 79. The total of the initial and supplementary movements of shaft 79 displaces the shaft through an even multiple of its differential positions. Correspondingly, item wheels 83 will have moved through the same number of their differential positions.

For example, depression of the "0" key releases common detent 104' from shaft 79 and moves "0" lever 76 to place its nose end 76' in the path of the "0" tooth 78. At "0" position of the parts, "0" tooth 78 is below "0" nose end 76' so that shaft 79 makes almost a full revolution before the "0" tooth engages the coasting nose end 78'. Then during rise of the "0" key, the "0" nose end 76' is withdrawn from the "0" tooth 78 and common detent 104' moves between a pair of teeth 103 of disk 102. Shaft 79 now rotates an additional amount until arrested by engagement of a tooth 103 with detent 104'. The total movement of the shaft will be through one complete revolution at the end of which the "0" stop finger 78 will again be in the position from which it started. Correspondingly, item wheels 83 meshed with drum 81 will have moved through one revolution from "0" position to "0" position.

If with the parts in "0" position, the "1" key is depressed, then "1" lever 76 will be moved forward and common detent 104' released from restraint on shaft 79. Shaft 79 will first rotate until the "1" finger 78 engages "1" nose end 76'; then on the upstroke of the key, the shaft will be released for a further, slight, movement until arrested by detent 104'. Similarly, depression 45 of the other keys will cause movement of the shaft from "0" position through the number of positions indicated by the depressed key.

The reason for effecting part of the movement of the shaft upon the down stroke and the remainder of the movement upon the up stroke of the key is to correctly time the release and arrest of shaft 79 by the oppositely moving nose end 76' and detent 104' and to provide clearance between detent 104' and teeth 103 when the detent 55 returns to restraining position.

If the shaft 79 were to move the complete differential distance upon the down stroke of the key, at the end of this movement, a tooth 103 would be exactly in line with detent 104'. Then 60 when the active nose end 76' released the stop finger engaged therewith, shaft 79 might rotate slightly before detent 104' could move above the aligned stop surface of the tooth 103 in front of the detent. As a result, the detent would fall 65 to engage the proper tooth 103 and shaft 79 would move an additional step. Further, if during return of the detent end 104', it were exactly in line with a tooth 103, then it might strike the edge of the tooth and be unable to move above 70 the tooth. By moving shaft 79 through less than its full differential distance upon the down stroke of the key, detent 104' can move with complete clearance above the surface of the tooth 103 below 75 it and the remainder of the differential movement

can be conveniently effected to bring the tooth and detent into engagement.

When shaft 79 and item wheels 83 on drum 81 have been moved by depression of a key 75 to a differential position other than "0", the following key depression will not cause movement of the shaft and item wheels through the same number of steps as represented by the number on the latter key, but through such a number of steps as will bring the shaft and wheels to the differential position corresponding to the depressed key. For example, if shaft 79 is in "1" position, its "1" stop finger 78 will be at the point initially occupied by the "0" finger. Now, if a "1" key 75 is depressed, shaft 79 will make a full rotation, in the same manner as described above in connection with the "0" setting, and under the successive control of the "1" nose end 76' and the common detent 104' the shaft will again be in "1" position.

If the shaft is in "1" position and a "2" key 75 is operated, then the shaft will move one step before it is completely arrested and the "2" finger 78 will be in the position in which the "0" finger 78 is shown in Fig. 4. This latter position may be referred to as the reference position. If shaft 79 has finger 78-8 at the reference position, then depression of the "4" key 75 will cause movement of the shaft through six steps to bring the "4" finger 78 to the reference position. Similarly, no matter in what differential position shaft 79 may be, depression of a key 75 will cause the shaft to move through the number of steps required to bring it to the position represented by the depressed key. Correspondingly, those item wheels 83 still meshed with drum 81 will move from any differential position they occupy to the new position represented by the key last depressed. For example, if a wheel 83 on drum 81 reads "4" and the "6" key 75 is depressed, this wheel 83 will move two differential steps to read "6".

As explained above depression of a key differentially sets all the wheels 83 meshing with drum 81 to the common position represented by the key. Thus, initially, all nine wheels are on the drum 45 and operation of key 75-8, for example, will set the nine wheels similarly, each to a "6" position.

In addition to setting wheels 83, operation of any of keys 75 controls an escapement mechanism to effect rotation of screw shaft 89 to an extent such as to move carriage 88 and wheels 83 one step to the left, as viewed in Figs. 1 and 2, thereby removing one wheel 83 from drum 81 and meshing this wheel with the right hand end 55 slide 10c.

Referring particularly to Figs. 1 and 11, the escapement-controlled means for rotating screw shaft 89 comprises gear sector 128 pivoted on stud 121 carried by frame plate 87. A spring 122 connected to sector 128 urges it clockwise (Fig. 11) to rotate gear train 123, 124, 125, and 126. Gear 126 meshes with a pinion 127 fixed to screw shaft 89. Also meshed with gear 126 is a pinion 128 (Figs. 1, 2, and 11) freely, rotatably, carried by shaft 79. Rigid with pinion 128 are two teeth 129 and 130 spaced apart along shaft 79 and having their radial, stop surfaces extending along the same diametral line and 180° apart.

Stop tooth 128 is normally in engagement with the nose end of a detent arm 131 rotatably carried by the left end of shaft 77 (see Fig. 1). Adjacent arm 131, shaft 77 has rigidly fastened to it another detent arm 132 located in the plane of tooth 128. The nose end of arm 132 is initially 70

in front of, slightly below, and remote from stop tooth 138. A lug 133 on arm 132 is held engaged with a stud 134 on arm 131 by a spring 135 connected to the stud 134 and to the frame.

Referring to Fig. 4, when a key 15 is depressed to set wheels 83, it rocks the connected lever 78 which in turn rocks common ball 107 clockwise. Underlying the left side of ball 107 (as viewed in Fig. 2) is the transversely bent lug 138' formed at the free end of an arm 138 pinned to shaft 77. Thus, when ball 107 rocks clockwise due to depression of a key, arm 138 and its shaft 77 are rocked similarly. Since detent arm 132 is pinned to shaft 77, it will also be moved clockwise (Fig. 11) to a position directly underlying stop tooth 138 and in the path of counterclockwise rotation of the latter tooth. At the same time, as arm 132 moves to the right, its lug 133 acts on stud 134 of arm 131 to move the latter, 20 against the pull of spring 135, in the same direction, thereby displacing the nose end of arm 131 from engagement with stop tooth 138.

The gear train comprising elements 120, 123, 124, 125, 126, 127, and 128 is now free to be rotated by the power of spring 122. Pinion 128 rotates a slight distance anticlockwise bringing its tooth 129 above and clear of the nose end of detent arm 131 and its tooth 130 into engagement with the top of detent arm 132. During this rotation of pinion 128, gear 126 rotates pinion 127 and its shaft 88 through a small angle, causing movement of the item wheels 83 on drum 81 slightly to the left (Figs. 1 and 2), but not to such an extent as to demesh the left hand one of the latter wheels from the drum.

The above, initial, escape action of the wheels 83 is the result of depression of a key 15. As previously explained, the depression of a key 15 also causes an initial setting operation to partially set the wheels 83 on the drum to the reading represented by the depressed key. During the, up stroke of a key, wheels 83 are given the final portion of the setting operation to complete their setting to the differential position selected by the key. Also, during the upward, return, stroke of the key, the escapement means operates to effect a supplementary rotation of shaft 88 to complete the lateral step of movement of carriage 88 and wheels 83. The completion of the setting of wheels 83 overlaps the early portion of the supplementary escape movement of carriage 88 and takes place before the left hand wheel 83 meshed with drum 81 has left the drum. In brief, the relation of the parts and their timing 53 are such that upon the down stroke of a key, all but a minor portion of the setting movement of the item wheels is carried out while only a slight portion of the escape step is effected, and upon the up stroke of the key, the slight, fractional, remainder of the wheel setting is completed and the major portion of the escape step takes place.

During the rise of the key, ball 107 moves counterclockwise (Fig. 4), permitting spring 135 to rock detent arm 131 to the left to position the nose end of the arm in the path of counterclockwise movement of associated stop tooth 129 which at this time is above the nose of arm 131 due to the initial escape movement. When arm 131 is rocked to the left (Fig. 11) by spring 135, through coaction of stud 134 and lug 133, arm 132 is similarly moved to the left, thereby withdrawing its nose end from engagement with tooth 130. This leaves pinion 128 free to rotate counterclockwise under the influence of spring 122 until tooth 129

engages the nose of arm 131. The parts of the escape means are then in initial position, shown in Fig. 11 and pinion 128 has completed a revolution. As a result of the supplementary, final, escape movement, gear 126 has rotated screw 8 shaft 88 to complete the lateral step of movement of carriage 88, and to thereby entirely remove from drum 81, the left hand one of the group wheels 83 meshed with the drum at the beginning of the last key operation.

In above manner, each time a key is operated, it causes all those wheels 83 which are still meshed with drum 81 to be differentially and commonly set to the position represented by the key and also causes escapement mechanism to shift 15 the wheels laterally to move the left hand one of these wheels off the drum and onto the first units order, slide 10c. In nine key operations, wheels 83 will be successively displaced to the left until they are all removed from 81 and in mesh with 20 the nine slides 10a, t, and c. Similarly, one to eight key operations will move the same number of wheels 83 off drum 81 and on to the same number of slides 10.

The reason for effecting the escapement movement in two parts and under control of two detents is because the length of time during which the operator holds a key depressed is indeterminate. If only one detent and escapement tooth were provided, there would be no assurance that 30 the detent after release by the depression of the key would be restored in time to arrest the tooth when it had made one revolution. By utilizing the two detents 131 and 132, at least one is always in position to engage the coacting tooth 35 129 or 130 and regardless of the length of time during which a key is held down, the escapement mechanism will move only one full step for each reciprocation of a key.

As an example of the setting and escape operations, assume the price of an article is 8.50, the kind of sale is "charge send" represented by code number 4, and that the clerk's number is 11. Initially shaft 78 is in "0" position and the nine wheels 83 are on drum 81. The operator first 43 depresses key 15-8, causing release of detent end 134' of lever 104 from disk 102. Shaft 78 moves almost eight differential steps from its "0" position until arrested by engagement of stop finger 78-8 with the nose end of the vertical arm of 50 lever 78-8, and drum 81 and the nine wheels 83 move synchronously with shaft 78. Depression of key 15-8 also caused release of detent 131 from tooth 129 of pinion 128, and simultaneously caused movement of detent 132 into the path of 55 movement of tooth 130 of the pinion. Spring 122 acts, upon release of pinion 128, to rotate the latter a slight amount until tooth 130 engages detent 132. This initial rotation of pinion 128 is accompanied by corresponding rotational movements of gear 126 and pinion 127. Shaft 88 of the latter pinion coacts with carriage 88 to shift the latter and the nine wheels 83 slightly to the left.

When the operator releases key 15-8, lever 65 78-8 rocks counterclockwise (Fig. 4), withdrawing its nose end from stop finger 78-8; simultaneously spring 135 moves detent end 134' above a tooth 103 of disk 102. Shaft 78 rotates a slight amount, completing its eight step movement from "0" position, and is then arrested by engagement of the detent end 134' with the tooth 103. During the latter rotation of shaft 78, the nine wheels 83 on drum 81 are correspondingly rotated and now set to read "8".

During rise of key 75-8, detent 132 is displaced from tooth 130 of pinion 128, and detent 131 is interposed in the path of rotation of tooth 129 of this pinion. Spring 122 acts now to rotate pinion 128 through the greater part of a revolution until tooth 129 engages detent 131, and the pinion is thus arrested in initial position. During the latter rotation of pinion 128, gear 127 rotates pinion 127 and its shaft 89 to shift carriage 88 and wheels 83 to the left for the major part of their escapement step. The differential setting of wheels 83 to their "8" positions is completed during the first part of this latter escape step, and then as the escapement continues, the first 15 wheel 83 from the left (Figs. 1 and 2) moves off drum 81 and onto unit slide 10c. At the end of the escapement step, this first wheel 83 reads "8" through sight opening 84 (Fig. 23). The other eight wheels are still on the drum.

20 The clerk now depresses key 75-5; shaft 79 rotates from its "8" setting an amount just short of seven steps before being arrested by engagement of stop finger 78-5 with lever 76-5. Upon the up stroke of the key, shaft 79 covers the remaining distance to its "5" position where it is arrested by detent 104.

25 The eight wheels which at the beginning of the operation of key 75-5 were on drum 81 are set now at "5". The reciprocation of the key effected escape of the carriage 88, bringing the left hand one of the latter eight wheels off drum 81 and onto unit slide 10c, where its reading "5" is visible through window 84. The left hand one of all nine wheels 83 had been set during the first 30 key operation to "8" and demeshed from drum 81, so that it was not affected by the rotation of drum 81 which took place upon the second key operation and remains at "8". The second escape operation of carriage 88 moves the latter wheel 40 83 onto the tens order slide 10c which is the second one from the right (as viewed in Fig. 1.)

35 In the same manner, keys 75 are successively depressed to set up 0, 4, and 11 on wheels 83. At the end of the six required key operations, the first wheel from the left will read 8, and be in mesh with units dollar order slide 10a, the next wheel will read 5 and mesh with dimes order slide 10a, the third wheel will read 0 and mesh with the cents slide 10a, the fourth wheel will stand at 4 and mesh with transaction slide 10t, and the fifth and sixth wheels will each read 1 and be in mesh with tens and units slides 10c. Through sight window 84, the reading 850 will appear under a suitable heading (not shown) denoting "amount", "4" will appear under a heading (not shown) denoting "kind of sale", and "11" will appear below a heading (not shown) indicating "clerk".

45 The last three wheels 83 will remain on drum 81, each wheel reading "1" as a result of the last key setting. Also, the last three higher order slides 10a, namely, the thousands, hundreds, and tens of dollar orders slides will be out of mesh with any of wheels 83. The abutment 90 provided on carriage 88 will be in front of these last three slides 10a, as has been explained before.

50 During the cycle of shaft 39, which is initiated by the operator subsequent to the setting operations, the item wheels 83 remaining on drum 81 are set to "0". For this purpose, a gear 136 at the right end of cam shaft 39 (as viewed in Figs. 1 and 3) carries at one side a cam piece 137 (see also Fig. 10). During the initial portion of revolution of shaft 39, cam piece 137 rides past the

free end of an arm 138 fixed to one end of a shaft 139, and thereby rocks shaft 139 clockwise (Fig. 10). The opposite end of shaft 139 has fast to it an upright arm 140 connected by a link 141 to an arm 142 loosely mounted on shaft 77 (see 5 Figs. 4 and 16). Arm 142 is in the same vertical plane as a special zero stop finger 78-0 secured to shaft 78 at the left of the ten-key controlled fingers 78 and disposed in the same relation to arm 142 as that of the key-controlled "0" finger 78 to nose end 76 of "0" lever 76. Arm 142 has a lug 143 held engaged with pin 144 on detent arm 104 by spring 105.

55 When cam lug 137 rocks shaft 139 clockwise, the shaft, through arm 140 and link 141, rocks arm 142 in the same direction. Arm 142, through coaction of lug 143 and stud 144, displaces detent 104 from the teeth 103 of disk 102, permitting spring 88 (Fig. 7) to rotate gear drum 81 and the item wheels 83 thereon until special "0" finger 78-0 abuts the nose end of arm 142.

60 Cam piece 137 holds arm 139 depressed long enough for shaft 78 to make substantially one revolution. When the cam lug rides off the end of arm 139, then spring 105 restores detent arm 104 which in turn restores arm 142. Arm 142 thereupon releases finger 78 and shaft 79 completes its movement to "0" position, where it is stopped by detent 104 engaging a tooth 103 of disk 102. Shaft 79, drum 81, and the item wheels 30 83 on the drum are now at "0" positions.

65 Subsequent to the above described setting of the wheels on drum 81 to "0", the spring actuator 88 of drum 81 is retensioned. This is done by a cam 145 (see Figs. 1, 3, and 7) fast to cam shaft 39. During the revolution of shaft 39, cam 145 acts on roller 146 of gear sector 88 to rock the sector counterclockwise, thereby retensioning spring 88. As sector 88 moves counterclockwise through gears 83 and 84, it rotates pinion 82 and 40 its shaft 82 in the same direction. During the counterclockwise revolutions of shaft 82, arm 89 on the shaft rides over pawl 100 without restraint due to yielding of spring 106. Any tendency of drum 81 to rotate counterclockwise during such 45 movement of shaft 82 is effectively prevented for the following reasons:

70 Counterclockwise motion of drum 81 would rotate shaft 79 clockwise (Fig. 7) and the latter movement would be effectively stopped by engagement of the top of detent end 104 with the tooth 103 directly above it (see Fig. 16) before shaft 79 could move one differential step. Further, if any item wheels 83 are still on drum 81, they are at zero positions and would also prevent tendency of the drum to rotate counterclockwise. This is because each wheel 83 has a home or zero position dog 148 (see Fig. 6a) which when the wheel is in zero position, is engaged with a flat shoulder 149 formed along shaft 60 85 of the wheels (see also Fig. 1).

75 For drum 81 to rotate counterclockwise requires clockwise movement of the wheels 83 on the drum, which are now at "0" position and cannot move clockwise because of dogs 148 abutting 65 shoulder 149 of shaft 85. As a result, drum 81 cannot move counterclockwise. Nor can the drum move clockwise, unless released by disengagement of detent 104 from teeth 103 of disk 102, which occurs only under control of keys 75 70 75 or cam 137.

80 Drum 81 has three times as many teeth as an item wheel 83 and when the latter is in "0" position, pawl 100 on the drum may be in either of three "0" positions, the one shown in Fig. 7, and 75

two others successively located one-third of a revolution apart. When restoring cam 165 leaves roller 146, arm 99 is in the position shown in Fig. 7. If pawl 160 is also in this position, then the pawl prevents clockwise rotation of arm 99. If pawl 160 is in either of the two successive positions further on in a clockwise direction, then spring 98 moves arm 99 clockwise 120° or 240° until it engages pawl 160. The parts 160 and 99 are now in required relation for effecting clockwise rotation of drum 81 during the next series of key-setting operations. The maximum possible number of rotations of item wheels 83 to be imparted by drum 81 is nine. The ratio of 15 gearing and the extent of movement of sector 98 are such as to be capable of rotating drum 81 through three and two thirds revolutions, providing therefore a surplus of two revolutions. Accordingly, even if after restoration of arm 99, 20 it has moved ahead under the force of spring 98 through two-thirds of a revolution, its remaining capacity for effecting three more revolutions of drum 81 is sufficient to furnish the maximum of nine revolutions of the nine item 25 wheels 83.

Those item wheels 83 which have moved off drum 81 and into mesh with punch slides 10a, t, and c control the setting of the slides to positions corresponding to the settings of the item 30 wheels. This is done as follows: Referring to Fig. 6, it has been explained that slides 10a, t, and c, are connected to arms 80 which are urged by individual springs 82 towards the left to move the connected slides in the same direction. This 35 movement is normally prevented by cross bar 88 engaging the front of arms 80. When the cross bar is permitted by cam 86 to move to the left, then springs 82 act on arms 80 to move them in the same direction. The arms in turn move 40 slides 10a, 10t, and 10c towards the left and through coaction of teeth 47 on these slides with the teeth of wheels 83 meshed with the slides, the wheels are rotated clockwise. The extent of this rotation is determined by engagement of the 45 zero position dogs 148 of the wheels with shoulder 149 of shaft 88 (see Fig. 6a). Slides 10a, t, and c thus move differential distances to the left until arrested by the zeroizing of the item wheel 50 83 meshed with the slides; and as a result, their punch pins 12 are positioned to perforate card T according to the items set up by keys 78. Any of slides 10a which have not been meshed with wheels 83 by the key operations, as when the amount 8.50 is set up, are arrested before they 55 move out of their "0" positions by the carriage abutment 98 which is located in front of these slides.

Also meshed with teeth 47 of slides 10a, t, and c are pinions 158 carried by the right hand ends 60 of nested shafts 161 (as viewed in Figs. 1 and 17), the opposite ends of which carry type wheels 48a, t, and c. Thus, when slides 10a, t, and c advance to differential positions under control of wheels 83, the slides rotate pinions 158 to set type 65 wheels 48a, t, and c to print the items set up by keys 78.

Those higher order slides 10a (at the left in Fig. 1) which have not been set under control 70 of wheels 83 but have been retained in "0" positions by abutment 98 do not rotate their pinions 158 and therefore the corresponding higher order type wheels 48a also remain in zero positions. The highest order wheel 48a has no "0" type lug since it is not necessary to print "0" in the highest 75 order of the amount while the remaining wheels

48a have "0" type to print "0" in an intermediate order of the amount item.

Subsequent to the setting of slides 10a, t, and c to differential positions, alining bar 36 moves into notches to exactly aline the slides, and the type 5 wheels geared thereto, in their various differential positions.

When slides 10a, t, and c have been set under control of wheels 83, the latter are at zero positions, and may be returned to drum 81. To restore these wheels to the drum, carriage 88 must be moved to the right (Fig. 1) by rotation of threaded shaft 88 in a clockwise direction (Fig. 11). This is done by a cam 158 on shaft 88 (see Figs. 1, 3, and 11). During the cycle of shaft 15 88, cam 158 engages follower roller 159 on gear sector 120 to rock the latter counterclockwise (Fig. 11). In so doing, spring 122 of the escapement mechanism is retensioned. As gear sector 120 moves counterclockwise, it causes clockwise 20 movement of pinions 127 and 128. Clockwise rotation of pinion 128 is not prevented by detent arm 131, since escapement tooth 129 merely cams the nose on this arm outwardly, as permitted by yielding of spring 135. 25

Clockwise rotation of pinion 127 moves its shaft 88 in the same direction. This rotation of shaft 88, through coaction of its threaded portion with carriage 88, moves the carriage and all nine 30 wheels 83 mounted between the sides of the carriage towards the right (Fig. 1). At the end of this movement, the nine wheels 83 are entirely demeshed from slides 10a, t, and c and again meshed with drum 81 in their initial positions.

During return of the wheels 83 to drum 81, it 35 is desirable to relieve the pressure between shoulder 149 of shaft 88 and the dogs 148 of the wheels. Further, the teeth of the wheels may not be in perfect alinement with the teeth of drum 81 and if dogs 148 were firmly engaged with 40 shoulder 149 of shaft 88, the wheels would be unable to rotate slightly so as to bring their teeth into line with the teeth of drum 81 and as a result, the wheels would be unable to return to the drum. The left ends of the teeth of drum 81 are rounded to facilitate meshing of wheels 83 therewith when the wheels slide back onto the drum. If the wheels are free to rotate, then if their teeth are not exactly alined with the drum teeth, the rounded ends of the latter teeth 45 cam against the teeth of wheels 83 to rotate the wheels slightly until their teeth are in alinement. To permit this alining rotation of wheels 83 and to relieve the pressure between dogs 148 and shoulder 149, shaft 88 is rocked clockwise (Fig. 4) under control of a cam 160 (Figs. 1, 3, and 4) on shaft 88. The cam is engaged by a roller 161 at the right end of a link 162 slidably guided at said end by shaft 88 and connected at the opposite end to a crank arm 163 depending from 50 shaft 88. 55

The high dwell portion of cam 160 rides off roller 161 after slides 10 have been locked in place by alining bar 36. A spring 164 thereupon moves link 162 to the left (Fig. 4), rocking arm 163 and shaft 88 clockwise. As a result, shoulder 149 of shaft 88 is moved away from zero pawls 148 of wheels 83 (see Fig. 6a), thereby preventing binding between the wheels 83, shaft 88, and drum 81 while the wheels are being returned into 70 mesh with the drum. At the beginning of the next cycle of shaft 88, cam 160 positively restores shaft 88 and shoulder 149 to their normal positions.

Following the completion of the punching op- 75

eration and upon restoration of the punch pins, alining bar 36 unlocks slides 10, as previously explained. Slides 10a and g, when unlocked by bar 36, are still restrained from advancing further by their engagement with tokens P and G. Slides 10a, t, and c, however, when released by bar 36, tend to advance under the influence of spring-actuated arms 60. To avoid this unnecessary advance of bars 10a, t, and c, their right hand portions (Fig. 6) are formed along their lower edges with ratchet teeth 165 for coacting with bell crank check pawls 166 rotatably carried by a rod 167 on which is also pivoted a yoke 168. The yoke carries a pin 169 between its sides acting to limit counterclockwise movement (Fig. 6) of check pawls 166 by springs 170. One side of yoke 168 has a pin and slot connection with a lever 172 which has a follower 173 engaging a cam 174 on cam shaft 38 (see also Fig. 3). While the slide aliner bar 36 is still locking slides 10 in their differential positions, cam 174 rocks lever 172 clockwise (Fig. 6) against resistance of a spring 175. Lever 172 thereby moves yoke 168 counterclockwise, and springs 170 cause check pawls 166 to follow and engage teeth 165 of slides 10a, t, and c. This prevents unnecessary advance of the latter slides when alining bar 36 subsequently unlocks the slides.

After the punching operation, cam 38 on shaft 30 acts on follower 65' of link 65 to rock arms 64 and 64' clockwise, causing bar 36 to restore arms 60 and slides 10. Restoration of the slides takes place while the check pawls 166 are still engaged with teeth 165 of slides 10a, t, and c. After complete restoration of the slides, cam 174 permits springs 175 to rock lever 172 anticlockwise (Fig. 6), and yoke 168 moves clockwise, causing its pin 169 to withdraw check pawls 166 from teeth 165.

The means cooperating with printing wheels 43 to effect an imprint on sales slip S will now be explained.

Printing means

Slip S is placed face upward on a printing table 180 (see Figs. 1, 2, 5, and 23) which is formed at the sides and at the rear with upwardly extending retaining lips 181. Table 180 is removably carried on the horizontal, top, flanges of an open box-like support 182 and secured to the rear flange 183 (see Fig. 1) by screws 184. Each of the sides 185 and 185' of support 182 is formed with a pair of elongated slots 186 for receiving guide studs 187 extending from frame plates 17 and 17' (Figs. 1, 2, 5); and by this means, support 182 and table 180 are mounted for horizontal, slidable movement. A spring 188 (Fig. 1), connected at one end to pin 189 extending from frame plate 17 and at the other end to support 182, constantly urges the table and support forwardly towards type wheels 43. The limiting forward position of the table is determined by the engagement of guide studs 187 with the rear ends of slots 186 of the support. In this position of the table, the slip S thereon has its top or first line s in printing position below type wheels 43.

Side 185 of table support 182 is formed at its right end (Fig. 5) with a pair of notches 190 followed by an inclined edge 190'. These notches 190 and the inclined edge selectively coact with the left end of a lever 192 urged clockwise (Fig. 5) by a spring 193.

An index or pointer 194 extending from the left side of table 180 (Fig. 23) coacts with figures 1, 2, 3 marked on a plate 195 secured to hous-

ing 40. When the table is in forward position, index 194 points to "1" on plate 195, the slip S has its first or top line s in printing position; and lever 192 is engaging the left hand notch 190 to impositively hold the table against movement. To position the table for locating the second line s in printing position, the operator moves the table towards the front of the machine until index 194 points to "2" on plate 195; and lever 192 coacts with the second notch 190 to maintain the table in second line position. To position the bottom or third line s in printing position, the table is moved towards the front of the machine until index 194 points to "3" on plate 195; and lever 192 coacts with edge 190' to hold the table against movement.

When the sales slip is placed on table 180, its leading edge moves beneath a guide plate 196 (Figs. 2 and 5) of thin spring steel which is solid below the spaces between adjacent banks of type wheels 43 and cut out below the banks of type wheels. The ink ribbon R is led from one spool 197 (Fig. 1) forwardly, then suitably guided upwardly, then horizontally between guide plate 196 and a similarly cut out guide plate 198 of spring material which keeps the ribbon away from the type wheels 43 so as not to interfere with rotation of the latter wheels. The ribbon is then guided downwardly and rearwardly to the other ribbon spool 197.

The means for feeding and reversing the ribbon feed need not be explained herein as such means are well-known and may be of any suitable type. Access may be had to the ribbon spools by removing table 180 from its carrier.

Below the type wheels is located a divided or sectional platen 200 carried by spring steel webs 200' (see Figs. 2 and 5) resting at their left or forward ends on screws 201 adjustably carried by a cross bar 202 of a bail 203. The webs 200' are formed with vertically bent ears 200a rotatably mounted on a shaft 204 journaled by frame plates 17 and 17'. Bail 203 is rotatably carried by the ends of shaft 204, and the right side of the bail (as viewed in Fig. 2) is formed as a bell crank lever 205 provided with a roller 206 riding on a cam 207 on cam shaft 38. A spring 208 urges the bail counterclockwise (Fig. 5). During the cycle of cam shaft 38, cam 207 rocks bail 203 clockwise (Fig. 5) to cause platen 200 to press the slip S and ribbon R against type wheels 43 to effect printing of a line s of the data set up on the type wheels.

After the printing operation, a stud 209 extending from the side of cam 207 rides past the inclined rear end 210 of lever 192 to rock the lever counterclockwise (Fig. 5) and release it from table support 182. If the support is in either position "2" or "3" when released by lever 192, then it is moved forwardly to position "1" by spring 188. Thus, after each printing operation, table 180 is automatically moved to locate the slip S for receiving an imprint in the first line s. This assures the first item of a transaction being printed in the first line s of the sales slip, and avoids the possibility that the operator may fail to set the table to this line when inserting a new sales slip.

The means for feeding a card T into punching position and ejecting the card subsequently to the punching operation will now be explained.

Card feeding and ejecting means

A supply of cards T is maintained in a maga-

zine 212 (Figs. 3 and 23), the top of which is part of housing 40, the bottom of which is a plate 213 and the back of which is a plate 214. The cards project through the open front end 5 of magazine 212 to be conveniently accessible for removal by the operator. After the key setting operations have been completed, the tokens P and G inserted, and sales slip S placed on table 180, the operator removes the top card from 10 magazine 212 and slides it between upper and lower guide plates 215 and 216 and into punching position. A three-sided border strip 216' is fastened to lower guide plate 216 and shaped to conform to the sides and the left edge including 15 the oblique corner of a card T (see Fig. 1). The border strip 216' combines with plate 216 to form a recess or pocket for snugly receiving the card and locating it in correct relationship to the punch slides 10.

20 When the card is inserted between guides 215 and 216, it moves without hindrance between the chordal, flat, portions of upper and lower feed rollers 217 and 218. Guide plates 215 and 216 are cut out opposite feed rollers 217 and 218 25 to permit the circular portions of the rollers to move into the passage formed between the guide plates to grip and feed the card forwardly. The shaft of upper roller 217 carries a gear 219 meshed with a gear 220 on the shaft of lower 30 feed roller 218. Gear 220 is driven by an intermittent gear 221 rotated through bevel gearing 222 from cam shaft 38.

Gear 221 has teeth through an arc of 72° for 35 meshing with gear 220 after the punching operation and thereby effecting a single revolution of feed rollers 217 and 218. The rotation of the feed rollers moves their round portions into the card passage between guide plates 215 and 216 to grip the card and feed it part way into a delivery receptacle 223.

The front wall of receptacle 223 is formed by plate 214 of the card supply pocket 212. The bottom of the delivery magazine is a plate 224 carried by the top flanges of standards 225 and 45 226 (see Figs. 1 and 3) and inclined downwardly at its left end (Fig. 3) to provide, in conjunction with the lower curved end of plate 214, a clear card passage in line with slots 11 of the punch slides. When feed rollers 217 and 218 feed the 50 card past frame plate 18, the card moves up along the inclined front end of bottom plate 224 of the receiving magazine 223 and onto the chordal, flat, portion of an ejecting roller 227.

The shaft of roller 227 has a pinion 228 for 55 coaxing with an intermittent gear 229 which has teeth along an arc of 72° which mesh with pinion 228 after the feed rollers 217 and 218 have completed their revolutions. The gear 229 is driven by bevel gearing 230 (see also Fig. 1) from cam shaft 38 and rotates ejecting roller 227 for one revolution. During this revolution of roller 227, its round portion moves, through a slot in plate 224, above the surface of the plate, and grips the partially ejected card to move the latter along the bottom of the stack of cards in magazine 223 while, at the same time, lifting the stack above the plate 224. At the end of the revolution of roller 227, the card is completely ejected into magazine 223 and rests on top of 65 plate 224.

A weight 231 on top of the stack of cards in magazine 223 provides the necessary friction between roller 227 and the card being ejected by the roller.

70 Delivery magazine 223 is closed at the top by

a door 232 (see Figs. 3 and 23) and a lock is provided to permit only authorized persons to open the door and remove the punched cards.

The upper part of an elongated, vertically disposed abutment plate 233 (see Figs. 3 and 9) 5 blocks card passage or slot 237 formed in frame plate 18. When the card moves into punching position, its leading end engages the upper part of abutment 233 and moves the latter to the right (Fig. 3) against resistance of a spring 234 connected to stud 235 of the abutment (see also Fig. 9). The movement of the abutment to the right is limited by engagement with the lip of a plate 236 secured to frame plate 18. Thus, the card is located properly in punching position by engagement of its leading edge with abutment 233; by engagement of its other edges with border strip 216'; and also, within the field of the slides 10, by engagement with the vertical sides of comb bars 20 and 21 (see Figs. 6 and 8). 20

Near its lower end, abutment plate 233 has a hole for loosely receiving a pin 238 extending from the side of a pivoted arm 239 which is urged clockwise (Fig. 9) by a spring 240. Pin 238 also passes loosely through a hole in a vertically disposed plate 241 (see also Fig. 2) lying flat against the face of plate 233. Both plates 241 and 233 are vertically slotted at their lower ends to straddle a stud 242 between the head of which and frame 18, the lower ends of the plates are confined in a manner to permit a limited rocking of the plates. Another stud 243 extending from frame 18 passes through aligned vertical slots of plates 233 to guide the latter for vertical movement. The plates are also vertically slotted 30 intermediate to straddle shaft 38. 35

Plate 241 is normally maintained throughout its length flat against the adjacent face of abutment 233 by a spring 244 surrounding stud 235, and confined between a washer 245 on the stud 40 and the face of plate 241. Projecting from plate 241 is a square lug 246. When plates 233 and 241 are in initial position, lug 246 abuts the radial edge 247 of a cam disk 248 on shaft 38 to prevent rotation of shaft 38 clockwise (as viewed 45 in Fig. 9). As shown in Figs. 3 and 10, gear 136 of shaft 38 is meshed with a gear 250 operated by crank handle 251. Two turns of the handle moves shaft 38 through a single revolution. Shaft 38 is permitted to move only counterclockwise (Fig. 10), reverse rotation being prevented by engagement of the teeth of gear 136 with a pawl 252 of spring metal. 50

When there is no card in punching position, 55 spring 234 holds plates 233 and 241 in the position shown in Fig. 3, and lug 246 of plate 241 abuts edge 247 of cam disk 248 to prevent rotation of shaft 38 clockwise, as seen in Fig. 9 or counterclockwise, as seen in Fig. 10. Insertion of a card in punching position moves plate 233 60 to the rear or right (as viewed in Fig. 3). As plate 233 moves to the right, through spring 244, it causes plate 241 to follow and displace its stud 246 from in front of edge 247 of cam 248. This releases cam shaft 38 for rotation by crank handle 251. 65

After the punching operation, edge 247 of cam 248 engages the free end of lever 238 and depresses it against resistance of spring 240. When arm 239 moves down, its pin 238 lowers plates 70 233 and 241. As a result, the upper end of plate 233 moves below card passage 237 of frame 18 and out of the path of advance of card T.

Feed rollers 217 and 218 then function to partially eject the card into magazine 223, and the 75

ejection is completed by roller 227. When the plates 233 and 241 are lowered out of the path of the card, they are no longer pressed to the right (Fig. 3) by the card, and therefore spring 5 244 moves the plates forward again. Stud 246 thereby is located in position to abut edge 247 of cam 248 and stop shaft 38 when the shaft has completed its one revolution. Just before the end of the revolution, the concentric high dwell 10 portion of cam 248 rides off arm 239, and spring 244 again raises the arm which in turn elevates plates 241 and 233 to place plate 233 in the path of the next card.

At the beginning of a cycle of shaft 38, plates 15 233 and 241 are in forward position, and stud 246 coacts with edge 247 of cam 248 to prevent counterclockwise movement of shaft 38. This also prevents turning of crank handle 251. At this time, if the operator attempted to turn 20 the crank, he would merely exert pressure by edge 247 of cam 248 against stud 246 of plate 241. If, while thus exerting pressure on the stud 246, the operator also moved a card into punching section, the forward edge of the card would 25 engage abutment 233 and move it to the right against resistance of spring 244. The pressure exerted by edge 247 on stud 246 may be sufficient to prevent plate 241 from moving to the right along with plate 233. Plate 233, however, 30 is able to move to the right without any interference from plate 241, merely compressing spring 244 when so doing. This yieldable connection, spring 244, between plates 233 and 241 permits plate 233 to be moved to the right by 35 the card although plate 241 is held in its initial position by the pressure exerted on its stud 246 by edge 247 of cam 248. If card abutment 233 and plate 241 were one piece, or were rigidly connected for common movement, then the pressure 40 exerted by edge 247 on stud 246 would prevent the card from moving the card abutment to the rear and as a result, the card might be damaged.

By forming the card abutment in two parts, 45 yieldingly connected to each other, injury to the card is prevented without interfering with the function of the abutment in preventing rotation of cam shaft 38 before a card is inserted.

After inserting the card, should the operator 50 still be unable to turn crank 251, he will understand that he is exerting too much pressure on the crank. He will then release the crank, and spring 244 will immediately snap plate 241 to the right to lie flat against abutment plate 233, 55 thereby releasing shaft 38 for rotation.

Summary

A summary of the operations required to record the sales transaction consisting of the 60 three items indicated on the sales slip shown in Fig. 13, will now be given.

Clerk No. 11 makes three "charge send" sales, the code designation of which is "4" to a customer having an account No. 209195. The first 65 article sold is a piano, having a code number "009". The date and department numbers have been pre-set, and the punch slides 18d and b and corresponding type wheels 43d and b are already in position to respectively punch and 70 print the date and department designations.

The customer's number and the kind of goods designations are set up by tokens P and G. The remaining items are set up by keys 75.

The tokens may be inserted first or else the 75 key set-up made first. Token G (see Fig. 15)

marked with code No. "009" is placed in pocket 82 and the customer's token P (see Fig. 15) in pocket 81.

Keys 75 are then operated one at a time to successively set up, in order, the first sales item 5 which includes the amount, 1250.00; the kind of sale; and the clerk's number 11. The order of operation of the keys must always be for amount, kind of sale, and clerk's number in succession 10 since this order is predetermined by the arrangement of slides 18a, t, and c and the corresponding printing wheels 43.

The first operation of a key 75 is to set up amount digit "1" of the highest order. The operation of the key causes rotation of a drum 81 15 (Figs. 1, 6, and 7) to set all the nine item wheels 83 initially meshed with the drum to the "1" position. The operation of the key also results in rotation of threaded shaft 80. Rotation of shaft 80 is controlled by an escapement mechanism shown in Fig. 11 and results in moving carriage 88 of item wheels 83 one step to the left (Figs. 1 and 2), causing the left hand wheel to move off the drum and into mesh with the right hand, units order, slide 18c. The reading "1" 20 on the latter item wheel is then visible through sight window 84 (Fig. 23) of casing 43.

The second key operation, to set up amount figure "2", results in the eight wheels 83 still 25 on drum 81 being commonly set to reading "2". The escape operation resulting from the second key operation moves the first left hand wheel 83 still reading "1" from units order slide 18c and into mesh with the next, tens order, slide 18c, and at the same time moves the second wheel 83 from the left off drum 81 and into mesh with units order slide 18c. The reading "2" of the latter wheel is then visible through 30 sight window 84 together with the reading "1" of the first item wheel.

The third key operation sets up amount digit 3 on the seven wheels 83 still on drum 81 and moves the nine wheels another step to the left, bringing the first wheel from the left (Fig. 2) 35 into mesh with slide 18t, the second wheel into mesh with tens order slide 18c, and the third wheel into mesh with units order slide 18c. In similar manner, the remaining digits 0.00 of the amount, the digit 4 representing "charge send", and the clerk's number 11 are successively set 40 up on wheels 83 by successive operations of keys 75.

At the end of the nine key operations, the nine 45 wheels 83 are all to the left of and demeshed from drum 81. The first wheel from the left is in mesh with "thousands" dollar order slide 18a, (the first from the left, Fig. 2), the second wheel is meshed with "hundreds" dollar order slide 18a, the third wheel is meshed with "tens" dollar order slide 18a, the fourth with dollars order slide 18a, the fifth and sixth with the dimes and cents orders of slides 18a, the seventh with slide 18t, and the eighth and ninth with tens and units order slides 18c. The readings on the wheels 50 are also visible through sight window 84 formed in housing 43.

Sales slip S may be placed on table 180 now or before the set up operations are begun. Table 180 is normally in the position indicated in Fig. 5 to locate the top line s of the slip at 55 printing position.

After completion of the set up operations, after the tokens P and G are inserted, and after slip S is in printing position, the operator inserts a card T between guides 215 and 216 into punching po- 60

sition. The insertion of the card moves plates 233 and 241 to the rear, withdrawing stud 246 from the path of movement of cam 248 on shaft 38 and thereby releasing the shaft. The clerk 5 now turns crank 251 through two revolutions to move shaft 38 through its single revolution cycle.

During this cycle of shaft 38, the slides 10p and g and corresponding type wheels 43p and g are set under control of tokens P and G; slides 10 10a, t, and c and corresponding type wheels 43 are set under control of wheels 83, printing of slip S is effected, card T is punched, and the card ejected.

The timing of the various operations will now 15 be described.

The setting of slides 10p, g, a, t, and c is controlled by cam 88 (Fig. 6). Referring to the fourth line of the timing diagram, Fig. 22, at 10° of the cycle, roller 88' begins to move along the 20 descending portion of slide bail cam 88, permitting springs 62 to move arms 60 to the left, the arms in turn acting on restoring bar 63 and link 65 to cause roller 88 to follow cam 88. During the next 85° of the cycle, cam 88 permits arms 25 60 to rock counterclockwise (Figs. 6 and 8) to advance slides 10p, g, a, t, and c.

Slides 10p and g advance to sense designation slots 48 of tokens P and G and are arrested by the tokens in differential positions corresponding 30 to the designations represented by the slot. As these slides move to their differential positions, through gears 46 and 42, they correspondingly set type wheels 43p and g.

As slides 10a, t, and c advance, between 10° 35 and 95° of the cycle, they rotate wheels 83 meshed therewith in a clockwise direction (Fig. 6) until the pawls 148 of these wheels engage shoulder 149 of shaft 85. The wheels 83 are thus zeroized, and slides 10a, t, and c are arrested in differential 40 positions determined by the values subtracted from the wheels in order to zeroize them and corresponding to the key set ups. As slides 10a, t, and c move to their differential positions, through gears 150, they correspondingly set type 45 wheels 43a, t, and c.

Thus, at 95° of the cycle, all the slides and type wheels have been set in positions to punch card T with the data of the first item of the sales transaction, and to print these data in the 50 first line s of the sales slip S.

Between 100° and 178° of the cycle, cam 88 rocks lever 32 clockwise (Fig. 5). Referring to the fifth line of Fig. 22, between 100° and 120° of this movement of lever 32, pins 321 (see also 55 Fig. 8) cammingly coat with the upper, inclined portion of slot 322 in ball 34, to depress slide liner or locking bar 36. At the end of this movement of bar 36, it has locked and aligned slides 10 and type wheels 43 in their exact, differential positions. Pins 321 then start moving downwardly along the now concentrically disposed edges 323 of ball 34.

At 130° of the cycle, pins 320 reach the bottom of slots 31' in links 31 and start depressing the 65 punch or pressure plate 26 (see the seventh line, Fig. 22). Between 150° and 165°, the punch pins 12 penetrate card T, then continue to move downwardly for the remainder of the clockwise movement of lever 32, which ends at 178°.

70 Cam 88' (Fig. 5) now starts rocking lever 32 counterclockwise (Fig. 5), and the lever moves in said direction between about 180° and 220° of the cycle. Between 180° and 195°, pins 320 move from the lower ends to the upper ends of slots 75 31' in links 31, and then start raising the punch

operating assembly. At 210°, stripper bars 23 of the operating assembly have raised the punches 12 clear of card T. The pins 321 then begin to coat with the upper, inclined portions of slots 322 of ball 34 to raise slide liner 36. As indicated 5 by the fifth line of Fig. 22, the slide liner 36 is completely unlocked from the slides at 220°, at which time the punch operating assembly has completed its upward, restoring movement.

At 180°, before bar 36 unlocks slides 10, cam 10 174 (Fig. 6) acts on lever 172 to cause check pawls 168 (see the sixth line, Fig. 22) to engage ratchet teeth 165 of slides 10a, t, and c. When bar 36 releases the slides at 220°, check pawls 168 prevent these slides from advancing under 15 the influence of springs 62. The check pawls are released from the slides at 340° of the cycle.

At 130° of the cycle, at the same time as the punch operating assembly begins to move down, cam 207 (Fig. 5) acts on arm 205 of ball 203 to 20 rock platen 200 upwardly, and between 170° and 205° (see the eighth line, Fig. 22), the platen coats with ribbon R and type wheels 43 to effect printing of a line of data s on slip S. Thus, the printing operation is completed before slide 25 alining and locking bar 36 starts releasing the slides at 210°.

The card is now ready to be ejected to storage magazine 223. At 175°, which is after punches 12 have penetrated the card, edge 247 of cam 248 30 (see Fig. 9) engages the nose of lever 239 to rock the latter counterclockwise. As lever 239 moves in this direction, its pin 238 lowers plates 241 and 233 (see the twelfth line, Fig. 22). At 185°, the abutment plate 233 has been lowered 35 completely out of the path of advance of the card, leaving the card free to be ejected by front feed rollers 217 and 218 and by rear feed roller 227.

At 218°, the teeth of gear 221 start meshing with pinion 220 to rotate feed rollers 217 and 218 40 for the next 72° of the cycle (see the tenth line, Fig. 22). Feed rollers 217 and 218 partially eject the card into magazine 223 and move the card onto rear feed roller 227. Rotation of feed roller 227 by gear 229 begins at 287° (see line 11 45 of the timing diagram, Fig. 22), and is completed at 357°, resulting in the complete ejection of the card into delivery magazine 223.

The remaining lines of the timing diagram will now be explained:

Between 5° and 15° of the cycle, cam block 137 (Fig. 10) causes arm 142 to place its nose end in the path of special zero stop finger 78'-0 of shaft 79 (see also Figs. 2, 4, and 16), and to simultaneously release detent 104' from teeth 103 of 55 disk 102 of shaft 79. Through the next thirty degrees of the cycle, spring 98 (see Fig. 7) moves shaft 79, drum 81, and those wheels 83 remaining on the drum after the key set-up to approximately zero position. The cam block 137 then rides off 60 arm 139', permitting spring 105 to restore detent arm 104 and special zero stop arm 142 to their initial positions, and detent arm 104 engages a tooth 103 of disk 102 to stop shaft 79, drum 81, and wheels 83 thereon in their zero positions. 65

Between 55° and 130° of the cycle, cam 145 (see Fig. 7) engages roller 146 of gear sector 96 to rock the sector counterclockwise and to retain 70 drum actuating spring 98.

At 120° of the cycle, cam 160 (see Fig. 4) releases link 162 for movement to the left by spring 164 to thereby rock shaft 85 clockwise, so as to withdraw its shoulder 149 from zero pawls 148 of item wheels 83. This action is completed at 135° and is for the purpose of relieving the pressure 75

between shoulder 149 and pawls 148 during return of wheels 83 to drum 81.

Between 140° and 230° of the cycle, cam 158 (see Fig. 11) engages roller 159 of sector 128, and rocks the sector counterclockwise to retension spring 122, and to cause rotation of screw shaft 89 clockwise. Rotation of shaft 89 moves item wheel carriage 88 to the right (Fig. 1) to return the item wheels 88 to their initial stations on 10 drum 81.

At 220°, the punching operation had been completed and bar 88 released from slides 10. At 225°, the printing operation had been completed and platen 200 restored. Thus, slides 10 may 15 freely be restored after 225°. At 240°, cam 88 starts moving link 85 to the right and bar 88 moves clockwise (Figs. 6 and 8) for the next 100°, picking up all the arms 68 and restoring them and their connected slides 10 to initial positions.

20 At 345° of the cycle, cam 88 (Fig. 8) rocks lever 88 clockwise. Through link 70 and pin 71, this withdraws latches 85 from slots 49 of the tokens and springs 54 act on members 83 to eject tokens P and G from their respective pockets 51 and 52.

25 At 350° of the cycle, stud 209 of cam 207 (see Fig. 5) rides past inclined tip 210 of lever 182 and releases the latter from table support 182. Spring 188 (Fig. 1) then restores table 180 which carries the sales slip, to the first line printing position.

30 This completes the series of operations required to print a single line s of data on sales slip S and to punch these data in a card T. To record the second sales item of the transaction on the same slip S, the latter is left on table 180 and the table 35 set in second line printing position. The keys 75 are then set up for the new amount, the same clerk number, and kind of sale. The same customer token P and a different token G, identifying the second article purchased, are inserted in 40 pockets 51 and 52, and then a second card T placed in punching operation. Shaft 89 is then moved by the operator through another cycle, resulting in printing the second line s and punching the second card T.

45 Similarly, the data shown in the third line on slip S are set up and printed and a third card punched.

While there has been shown, described, and pointed out the fundamental features of the invention as applied to a single modification, it will be understood that various omissions, substitutions, and changes in the form, details, or operation of the device illustrated may be made by those skilled in the art without departing from 50 the spirit of the invention. It is the intention, therefore, to be limited only as indicated by the scope of the following claims.

What is claimed is:

1. In a machine for punching a record card 60 having columns of index point positions; the combination of a plurality of parallel, elongated slides, each for moving independently of the others along a different one of the card columns, each said slide being cut intermediately with an elongated slot extending parallel to the length of the slide, the slots of the several slides being aligned to permit a card to be inserted through the slots into punching position with respect to the slides, spaced comb bars extending through said 65 slots transversely of the slides and having teeth extending between the slides and engaging the portions of the slides bounding said slots for stiffening the intermediate portions of the slides against bending out of their planes during the 70 movement of the slides along their associated 75

card columns; and punch pins carried by the slides, for punching the index point positions of the card columns.

2. The machine such as defined in claim 1, said spaced comb bars engaging the opposite sides of 5 the card during its insertion into punching position and while it is in punching position to thereby serve as card guiding and locating means.

3. In a card punching machine; a punch of 10 non-circular cross-section for punching a non-circular hole in a card, a carrier for the punch slotted to receive the card to be punched, said carrier comprising integral portions above and below the card slot channeled to slidably embrace part of the cross-section of the punch, an element rigidly fastened to the carrier above the card slot and complementarily channeled to slidably embrace the complementary part of the punch cross section, and a second element rigidly fastened to the carrier below the card-receiving 15 slot and channeled similarly to the first element, the channeled portion of the carrier and the element above the card slot coacting to form an upper punch die, and the second element and channeled portion of the carrier below the card 20 slot forming a lower punch die.

4. In combination; a record-bearing member 25 having an elongated hole to represent a value proportional to the length of the hole, a sensing device movable into said hole for a differential amount dependent on the length of the hole and arrested by engagement with the upper and/or lower end of the hole, and differentially operable means controlled by the sensing device in accordance with the differential movement of the 30 device.

5. In combination; a record-bearing member 35 having an elongated hole to represent a value proportional to the length of the hole, a slide movable into said hole and effectively tapered at 40 its forward end to engage either the upper or lower end of the hole after a movement dependent on the length of the hole and the value represented thereby, and value manifesting means differentially controlled by the slide according to 45 the value of said hole.

6. In combination; a record-bearing member having an elongated hole to represent a value proportional to the length of the hole, a slide 50 movable into said hole and having at one end a series of value steps of different effective heights and arranged one behind another to selectively engage either the upper or lower end of the hole in accordance with the length of the hole and to thereby arrest the slide after a differential movement dependent on the value represented by the 55 hole, and recording means controlled by the slide according to the differential movement of the slide.

7. In combination; a record-bearing member 60 having data representations, a pocket into which the record-bearing member is insertable, a device for sensing the data representations of the record-bearing member, yieldable means for moving the device towards the member to sense 65 its data representations, a cyclically operable mechanism for causing said yieldable means to operate, and means coacting with the device for restraining its operation by the yieldable means during a cycle of said mechanism in which such 70 record-bearing member is absent from said pocket.

8. In combination; a record-bearing member having data representations, a pocket into which 75 said member is insertable, a device for sensing

the data representations, cyclically operable mechanism for causing operation of the device to sense the data representations of the member, means normally effective, in the absence of a 5 member from the pocket, to disable the sensing device from operation while the operating mechanism is going through a cycle, an element for locking the record-bearing member in the pocket after insertion, and connections between said 10 element and disabling means for rendering the disabling means ineffective when the record-bearing member is locked in the pocket by said element.

9. In a punching machine; the combination 15 of a punch pin, a slide carrying the punch pin, a value selector, means for differentially setting the value selector from a zero position to a position representing a selected value, operating connections between the slide and the value selector, and means for moving the slide, after the value selector has been set up, to return the value selector to its zero position and thereby to set the punch pin in accordance with the selected value.

25 10. In combination; a group of elements having differential positions representing digital values, a common actuating device for said elements, keys operable for causing said device to differentially set said elements, means for successively removing the elements after each setting operation from coaction with the actuating device, some of said elements remaining in coaction with said device after a certain number of setting operations, and cyclically operable means 30 other than said keys for causing the actuating device to set said remaining elements to a common digital position.

11. In combination; card punching mechanism, a cyclically operating actuator for the 40 punching mechanism, a movable device initially engaging a part of the actuator for restraining operation of the latter, and a movable card abutment yieldingly connected to said device and engaged by the leading edge of the card, when the 45 card is advanced to punching position, to be moved by the pressure of the card to a card stopping position and during such movement effecting movement of aforesaid device to release the latter from restraint on the cyclically operating 50 actuator, said device when undue pressure is exerted thereon by the part of the actuator with which it is engaged remaining in initial restraining position without interfering with movement of the card abutment, by the card, to the card 55 stopping position.

12. In combination; a record member with elongated holes of different lengths significant of different values, sensing elements, means for moving the elements to be arrested, each one by 60 engagement selectively with different edges of a value hole, after differential movements dependent on the lengths and value significances of the holes, and punches and dies for punching a record form between them with value representations 65 selected by said sensing elements in accordance with their several differential movements.

13. In combination; a record member with elongated holes of different lengths significant of different characters, sensing elements, means for moving the elements to be arrested, each one by 70 engagement selectively with different edges of a character hole, after differential movements dependent on the lengths and character significances of the holes, and character manifesting

means selectively controlled by the sensing elements in accordance with the several differential movements of the latter for manifesting the characters represented by the holes of the record member.

14. In a machine of the class described; punching mechanism including punches and dies to perforate parallel columns of a record form with data or value representations, a keyboard having a plurality of value keys, a plurality of operations of which are effected to select a plurality of value representations to be perforated by the punches and dies in selected value columns of a single record form, a token having characteristics significant of data for classifying the values selected by the keys, means for freely insertably receiving the token when manually inserted by an operator, means to temporarily retain the inserted token in a control position, means controlled by the token characteristics while the token is in control position for selecting the classifying data designations to be perforated by the punches and dies in selected classifying data columns of the aforesaid single record form, and means for automatically releasing the retaining means from the token after the aforesaid record form has been punched with the key-selected and token-selected value and data representations.

15. In a machine to punch index positions of columns of a record with value representations; punching mechanism including devices adjustable to select the index positions of the columns to be punched, value selectors, value keys, means controlled by successive operations of the keys to successively enter values into the selectors, means 35 to successively operatively connect the selectors, after receiving the key-controlled entries, with successive ones of said devices, means to transfer the value standings of the selectors to the devices by zeroizing the selectors to thereby adjust the 40 operatively connected devices according to the values standing on the selectors prior to their zeroizing, and means for then effecting operation of the punching mechanism for punching the record columns in the index positions selected 45 by the adjustment of said devices.

16. In a machine to punch index positions of columns of a record with value representations; punching mechanism including devices adjustable to select the index positions of the columns 50 to be punched, value storing means, a set of ordinal value keys, each corresponding to a different ordinal value, means controlled by successive operations of the same or different ones of said keys for entering values in succession into the 55 storing means, means controlled by the storing means in accordance with the values entered therein for adjusting the devices to select the index positions of the record columns to be punched, and means for then effecting operation 60 of the punching mechanism to punch the record columns according to the adjustment of the aforesaid devices.

17. The machine as defined in claim 16, the storing means comprising adjacent, relatively 65 movable value storing elements, and means controlled by the keys upon successive operations thereof for successively correlating the elements of the storing means, after receiving different key-controlled value entries, with adjacent ones 70 of said adjustable devices.
